SHOE MACHINE

Fred Ashworth, Wenham, Mass., assignor to
United Shoe Machinery Corporation, Flemington, N. J., a corporation of New Jersey

Application August 25, 1943, Serial No. 499,951

33 Claims. (Cl. 112—46)

The present invention relates generally to sewing or other similar machines more particularly of the type for operating upon shoes and is herein disclosed as embodied in a machine arranged for use in the manufacture of stitchdown shoes in which a welt is sewed to the outturned upper and projecting margin of an outsole while the parts presented to the machine are supported upon a last.

An important object of the invention is to avoid waste of welt and loss of time in operating the machine and to enable shoes of the stitchdown type to be sewed without the necessity of careful attention or exercise of particular skill on the part of the operator.

Another object is to avoid the necessity of performing a separate welt trimming operation on such a shoe after the sewing operation is completed and to secure accurate positioning of the welt end on the outturned upper of an unsewed shoe when a new sewing operation is to be started.

Previous attempts to relieve the operator of the necessity of careful attention and exercise of particular skill while sewing the welt to stitchdown shoes in order to prevent waste in welt have been directed toward the provision in a sewing machine of a knife for severing the welt at a location within a guide for the welt close to the point of sewing operations. While severing the welt within the guide is of some benefit, it still requires some effort and skill on the part of the operator to estimate in advance the amount of welt required in finishing a seam.

As will appear more fully hereinafter, the principal feature of the present invention is embodied in a sewing machine having a welt cutting knife mounted for operation on a portion of the welt while in actual sewing position on the outturned shoe upper, thus enabling the welt to be severed at a location so close to the sewing point that no special effort is required of the operator in estimating the length of welt required in finishing a seam and no separate trimming operation is needed after the shoe is removed from the machine. Preferably, the welt is cut by the knife at a location a fraction of a stitch length ahead of the sewing point. In this way, the final stitch of a seam will maintain the severed end of the welt securely in position on the shoe. To insure cutting at the proper time without stopping the machine, the machine is provided with a driving and stopping mechanism which actuates the knife automatically in the manner referred to and causes the machine to be brought to rest immediately thereafter. As a means for simplifying

the operation still further, suitable clamping means is provided and actuated to grip the welt when the machine is brought to rest so that, in case the knife does not cut off the welt completely, a pull on the welt while the operator is removing the shoe from the machine will act to sever the ends at the cut.

In one form of this feature of the invention, the knife is arranged so that it will not cut the welt entirely through. When thus operated, the unsevered section of the welt acts to withdraw the cut portion past the sewing point in the machine when the shoe is removed, the welt clamping means limiting the amount of withdrawal to the exact length required in starting a new seam. While this feature is particularly useful in machines for sewing welts to stitchdown shoes, the arrangement is also applicable to advantage in other types of sewing machines and in other machines in which a welt is attached to a work piece by means other than stitches.

As illustrated, the welt clamping means is constructed to yield a predetermined length of welt before causing the welt to be severed, which length of welt is regulated to permit the cut section to be carried, during the movement of the shoe past the attaching point of the machine, to a position where the end remaining in the machine after severing will project sufficiently to enable attachment with certainty to the work and with the end of welt overlapping the attaching point of the machine in starting a new operation.

When applied to a machine for sewing a welt to the outturned upper of a stitchdown shoe, it is desirable to avoid severing the welt in the middle of a seam when it is necessary to bring the machine to rest on account of thread breakage or other causes. Accordingly, the invention contemplates the provision of a safety device constructed and arranged to be tripped by the operator of the machine just before the end of the seam is reached, which device will prevent the operation of the welt cutting knife at all times other than at the end of the seam. In certain cases, however, such a safety device may be dispensed with since the cut in the welt, unless the welt is completely severed, will not be detrimental to the appearance of a shoe particularly if a stitch is laid across the cut to form a continuous seam. This result can be obtained, when it is desired to stop the sewing operations between the ends of a stitchdown seam, if, after the machine has been brought to rest, it is restarted without removing the shoe.

These and other features of the invention con-

sist in the novel and improved devices, combinations and arrangements of parts hereinafter described and claimed, the advantages of which will readily be understood from the following description taken in connection with the accompanying drawings illustrating one embodiment of the invention.

In the drawings;

Fig. 1 is a view in front elevation of the upper part of a machine embodying the present invention;

Fig. 2 is a view in perspective of a welt cutting knife employed in the machine of Fig. 1;

Fig. 3 is a detail view in right side elevation of certain portions of the machine of Fig. 1, shown partly in section, illustrating the mechanism for controlling the operation of the welt cutting knife and welt clamp;

Fig. 5 is a view in front elevation of the knife and its actuating lever;

Fig. 6 is a plan view of the welt clamp and guide roll;

Fig. 7 is a view in side elevation of the parts shown in Fig. 6;

Fig. 8 is a sectional view in front elevation of the welt clamp, indicating the positions of the clamp parts during sewing operations;

Fig. 9 is a similar view of the clamp with the parts in welt gripping positions at the end of a seam;

Fig. 10 is a similar view of the welt clamp after the shoe has been withdrawn from the machine and the welt completely severed at its point of attachment to the shoe;

Fig. 11 is a sectional view, taken along the line XI—XI of Fig. 7;

Fig. 12 is a detail view of the support for the welt clamp and a clamp latching plunger for preventing retraction of the welt after being withdrawn and severed;

Fig. 13 is a detail view of the carrier for the welt clamp;

Fig. 14 is a detail view of the movable member of the welt clamp;

Fig. 15 is a view, on an enlarged scale, looking in the direction of the arrow in Fig. 3, of a portion of the welt cutter actuating mechanism;

Fig. 16 is a view in front elevation of the parts illustrated in Fig. 15;

Fig. 17 is a sectional view, taken along the line XVII—XVII of Fig. 16, illustrating the inoperative positions of the parts;

Fig. 18 is a sectional view, taken along the line XVIII—XVIII of Fig. 16;

Fig. 19 is a detail view, partly in section, of a portion of the manually controlled connections between the driving and stopping mechanism and the welt knife actuating mechanism, taken just after the welt knife mechanism has been rendered operative;

Fig. 20 is a similar view of the same mechanism after the welt knife mechanism has operated and is thereafter rendered inoperative;

Fig. 21 is a perspective view, partly broken away, of a stitchdown shoe after being sewed on the illustrated machine;

Fig. 22 is a similar view, on an enlarged scale, illustrating the method of operation of the welt cutting knife;

Fig. 23 is a sectional view, on a further enlarged scale, of the projecting marginal portions of a shoe as they would appear from the front of the machine at the end of an outseam

except for completing the final stitch, the welt cutting knife being in actuated position;

Fig. 24 is a similar sectional view, illustrating the marginal portions of a shoe being operated upon after the welt cutting knife has acted and has been withdrawn from the welt and the shoe has been fed a stitch length, ready for insertion of the final stitch in the seam;

Fig. 25 is a sectional view of the same portions of the shoe after the final stitch has been inserted;

Fig. 26 is a sectional view of the same portions of the shoe, illustrating the positions of the end of welt remaining in the machine and after being severed from the shoe, and of the thread after being trimmed manually by the operator;

Fig. 27 is a similar sectional view, illustrating the position of a new shoe in relation to the welt end remaining in the machine in starting a new seam;

Fig. 28 is a perspective view of the welt, illustrating the nature of the cut formed by the knife; and

Fig. 29 is a similar view, partly broken away, illustrating the relation of the cut ends of the welt after being severed at the completion of a seam by withdrawing the shoe from the machine.

The machine illustrated in the drawings is an outsole shoe sewing machine constructed and arranged to insert a lockstitch outseam in a shoe and is similar, except as hereinafter described, to the machine disclosed in United States Letters Patent No. 2,271,611, granted February 3, 1942, upon an application filed in the names of Fred Ashworth and Carl F. Whitaker, to which reference may be had for a more complete explanation of the construction and manner of operation of the stitch forming devices and their actuating mechanisms.

The features of the invention embodied in the present machine are intended particularly to facilitate and simplify the application and attachment of a welt to a stitchdown shoe, such as illustrated in Fig. 21 of the drawings, provided with an upper 2, an insole 4, an outsole 6 and a finish welt 8. The purpose of the welt 8 is to reinforce the outseam, indicated at 10, connecting the outflanged marginal portions of the upper 2, the insole 4 and the outsole 6 and to impart a pleasing appearance to the completed shoe. In attaching the welt, the outseam usually is started at a point, indicated at 11, along the inside edge of the shank in a shoe and is continued about the shoe until the same position is reached upon return of the shoe to the beginning of the seam. The usual practice is to provide the end of the welt first applied to the shoe with a bevel cut across the welt and, upon completion of the seam, to sever the welt at the proper location with a second bevel cut the surface of which will register with the surface of the bevel cut at the end first applied to the shoe, thus forming a smooth, finished joint in the welt. In regular commercial work, the welt is cut by hand either after the seam is completed or by stopping the sewing operations a suitable distance away from the end of the seam to provide space for cutting the welt so that its end surfaces will register with each other. It is then necessary to insert additional stitches to complete the seam. In either manner of forming the seam and cutting the welt, particular attention and skill must be exercised by the operator to avoid loss of time as well as damage to the shoe.

Automatic, or semiautomatically actuated, welt

cutting knives have been provided in sewing machines acting within a welt guide at a distance from the sewing point on the shoe to form a smooth joint between the ends first attached and last attached to the shoe. While such knives are effective for the purpose intended, they necessitate careful observation not only of the point of sewing operations in the machine but also of the approach of the first end of welt applied to the shoe, sufficiently in advance of the position at which the welt cutting knife should be actuated. If the distance between the advancing end of the welt first applied to the shoe and the sewing point is shorter than the distance between the sewing point and the welt cutting knife, the bevel surfaces at the ends of the welt cannot be brought into accurate register. If the distance between the advancing welt and on the shoe is too short, the end severed by the cutting knife will overlap the end on the shoe, thus causing an irregular appearance.

To avoid these difficulties in the present machine, a welt cutting knife 12 is provided, acting directly on the shoe at a location within a fraction of a stitch length ahead of the sewing point. When so located, the full attention of the operator may be concentrated at the sewing point and, as soon as the advancing, leading end of the welt on the shoe approaches to within a stitch length of the sewing point, the welt cutting knife may be actuated across the welt with the result that an accurate registration between the welt ends is produced and the seam may be completed by inserting an additional stitch securely attaching the final cut end of the welt to the shoe.

The operation of the knife 12 in cutting the welt and forming the joint between the first and final ends of the welt is clearly illustrated in Figs. 22 to 29, inclusive. The welt, after being applied and sewed nearly to the starting point 11 in the seam, is acted upon by the knife which is disposed at an angle to the general plane of the shoe parts being operated upon. The welt is led against the projecting marginal portions of the shoe in a direction generally parallel to the plane of the knife, through a bend just before reaching the sewing point and into the plane of the shoe parts. The knife 12 is arranged to cut the welt along the bend, acting with its sharpened edge 13 against the substance of the outflanged shoe upper as a cutting block. By so arranging the knife, the sharpened edge, when in active position, may be located so close to the sewing point that no separate manual trimming operations will be required in the welt after the shoe is removed from the machine. Since the knife is arranged to act on the welt within a stitch length ahead of the sewing point, the final stitch in a seam, after the knife is actuated, will secure the final severed end of the welt in place, as illustrated in Fig. 25. Thus, the welt cutting knife may be actuated automatically through connections to a driving and stopping mechanism for the machine so as to require attention on the part of the operator only sufficient to observe the approaching end of welt already attached to the shoe as it reaches the location one stitch in advance of the sewing point, the machine being stopped within a single sewing cycle by the driving and stopping mechanism.

The stitch forming devices of the machine include a curved hook needle 14, a curved awl 16, a rotary shuttle for passing each loop of needle thread about a locking thread case 18, a looper 20 and other thread handling members actuated

by simultaneously rotating sewing shafts 21 and 22 similar to those disclosed in the Ashworth and Whitaker patent above mentioned. The shoe is clamped in the machine during sewing by a work support 23 and a presser foot 24, acting together alternately to clamp and feed the shoe. To direct the welt 8 into a position on the outturned shoe upper in advance of the sewing point, the work support 23 is provided with a welt guide 25 in the form of a slot in that edge of the work support first engaged by the advancing marginal portions of the shoe.

As illustrated in Fig. 27, the shoe applied to the machine comprises only the lasted upper 2, an insole 4, and the outsole 6 temporarily attached to the insole. When the unsewn shoe is applied to the work support, a short length including a bevel cut end of the welt 8 projects from the work support and comes into engagement with the outflanged margin of the shoe upper on the work support. As soon as the machine is started, the parts are clamped and a stitch is inserted through the bevel cut welt end first applied to the shoe, the welt being drawn through the guide 25 with the shoe as the sewing continues until the seam has nearly been completed. To insure the best results, the first bevel cut end of the welt sewed to the shoe is so located with respect to the sewing point that the first stitch of the seam will be inserted within a stitch length of the bevel cut end. When the operator observes the approach of the advancing end of the welt first sewed to a position within a stitch length of the final end of the seam, the cutting knife is set into operation, one additional stitch is inserted and the machine is thereafter brought to rest.

The welt cutting and end beveling knife 12 is best shown in Fig. 2 and consists of a thin elongated blade slidably mounted at its upper end to move within the welt guide 25 parallel to the path taken by the welt as it is carried through the guide above the knife. To actuate the knife, the lower end is supported on a pivot 26 (see Figs. 3, 4 and 5) carried by one arm of a bell crank 28 rotatable about a downwardly extending screw 30 threaded at its upper end within a lug formed at the right-hand side of the work support 23. Another arm of the bell crank 28 is slotted to receive an angularly bent end of a link 32 loosely supported in an opening of a plate 34 fastened to the frame of the machine. The upper end of the welt cutting knife, being guided beneath the welt in the guide 25, acts against the bend of the welt between the guide and the shoe, in the manner outlined, whenever the bell crank 28 is rocked on its fulcrum stud. The sharpened edge of the welt cutting knife is held out of engagement with the welt by a coil spring 36 surrounding the link 32 and pressing at one end against the plate 34 to draw the link rearwardly. Cooperating with the other end of the spring 36 is a bifurcated block 38 secured to the rearward end of the link 32, between the bifurcations of which block is pivotally connected a downwardly extending arm on a yoke-shaped support 40 having downwardly extending lugs pivoted to swing on a horizontal shaft 42 secured in the machine frame.

The support 40 is a part of the welt knife actuating mechanism and carries a rearwardly extending follower lever 44 (see also Fig. 15) movable about a substantially vertical fulcrum screw 46 the axis of which is substantially at right angles to the axis of the shaft on which the sup-

port 40 is pivoted. To limit the rotation of the support 40 on the shaft 42, the downwardly extending arm of the support carries a set screw 45 engaging a portion of the machine frame. One arm of the follower lever has a rounded end formed to engage a cam disk 47 secured to the sewing shaft 21. The disk is formed with a radial projection 48 for depressing the round ended arm of the follower lever 44 when the lever is held in the path of the projection. When the follower lever is actuated by the projection 48, motion is transmitted through the support 40 and its downwardly extending arm to actuate the knife against the welt. After the projection 48 has actuated and passed the follower lever 44, the spring 36 withdraws the sharpened edge of the knife from the cut formed in the welt and returns the support and follower lever to their original positions. During continued rotation of the knife actuating cam disk, an axially inclined wedging surface 50, best shown in Figs. 1 and 3, engages one side of the round ended arm on the follower lever 44 to swing the lever on its fulcrum screw 46 moving the round ended arm along the sewing shaft 21 clear of the path of the projection 48, thus preventing a second operation of the welt cutting knife.

The follower lever 44 is yieldingly urged in a direction to bring its round ended arm into the path of the projection 48 on the cam disk 47. Surrounding the fulcrum screw 46 is a torsion spring 52 (best shown in Fig. 15) acting against a pin 54 on the lever and a pin 56 on the pivoted support 40. To hold the arm of the follower lever away from the projection 48 on the actuating cam disk and the welt cutting knife inoperative, there is mounted on a guide block 57 carried by the support 40 a latch 58 pivoted to swing about a shouldered screw 60 toward and from a second arm on the follower lever. As shown in Figs. 17, 19 and 20, the latch engaging arm of the follower lever is beveled along one edge to enable it to enter readily beneath the latch, and the latch is formed with a downwardly extending lug between which and the pivoted support 40 is compressed a coil spring 62 for retaining the latch in engagement with the follower lever. When the latch releases the follower lever, the torsion spring 52 swings the follower lever into the path of the projection 48 to cause actuation of the knife.

At the end of a seam, the follower lever 44 is released from the latch 58 to set the knife actuating mechanism in readiness for operation by connections with the driving and stopping mechanism of the machine. These connections include a flat-sided pin 64 projecting from one side of the latch 58, a three-armed hook member 66 rotatable on a pivot screw 68 carried by a vertically movable slide 70 confined within a suitable guideway in the block 57 on the pivoted support 40. The hook member is yieldingly urged toward a position with its hooked lower end engaging the latch pin 64 through the action of a tension spring 71 connected between the hook member and an upstanding portion of the block 57. The lower end of the slide 70 has a threaded opening to receive the upper end of a guide screw 72 passing loosely through a passage of the pivoted support 40. Surrounding the guide screw 72 between its lower headed end and a horizontal surface on the support 40 is coiled a compression spring 74 for retaining the slide 70 in its lowermost position where the hook member 66 may engage the pin 64 in the latch 58. To release the

latch from the follower lever, the slide 70 is raised against the force of the spring 74 and is secured to one end of a flexible cable 76 clamped within it by a screw 78. The flexible cable 76 passes through a sheath 80 held at one end within a socket formed between yielding portions of the pivoted support 40 and secured against the sheath by a clamp bolt 82. The other end of the flexible cable 76 is connected to a block 84 (see Fig. 3) carried by a movable part of the driving and stopping mechanism, the sheath 80 at its other end also being held within a clamping fixture 86 on the machine frame. The arrangement of the hook member 66 is such that, when the flexible cable 76 moves within its sheath, the slide 70 is raised, and the hook member releases the latch from the follower lever 44, causing the welt cutting knife to perform its operation. As soon as the follower engaging latch 58 is disconnected from the follower, a horizontal arm of the hook member 66 is brought against a pin 88 (see Fig. 17) on the upstanding portion of the guide block 57 to disengage the hook member from the pin 64 on the latch 58 so that, after the welt cutting knife has been actuated, the follower lever 44 will immediately be relatched in its inoperative position.

In sewing about the forepart of a shoe, it may be necessary to bring the machine to rest as a result of thread breakage or improper adjustments in the stitch forming devices, and it is not desirable to cut the welt under such circumstances. To avoid cutting the welt along the forepart of a shoe, the connections between the welt cutting knife actuating mechanism and the driving and stopping mechanism are disconnected after each actuation of the welt cutting knife when the latch 58 is released from the hook member 66, as indicated in Figs. 19 and 20. The hook member is retained in disconnected relation with the pin 64 on the latch 58 by a manually actuated latch 90 pivoted on a screw 92 received in the guide block 57. The latch 90 has connected to it a spring 94 stretched between a pin on the latch and the pin 88 to draw the latch against an upstanding arm of the hook member and to cause the hook member to be latched out of engagement with the follower engaging latch 58. By reason of the manually actuated latch 90, the operation of the driving and stopping mechanism in bringing the machine to rest will prevent the knife actuating mechanism from causing the welt to be cut.

In order to actuate the connections between the driving and stopping mechanism and the follower engaging latch 58, the manual latch 90 is provided with a forwardly extending handle portion which may be depressed by the operator while the final stitches of a seam are being sewed and before the driving and stopping mechanism is actuated at the end of a seam. Pressing the handle portion of the latch 90 releases the hook member and enables it to engage the pin 64 on the follower engaging latch so that, when the driving and stopping mechanism is actuated, the welt will be cut.

The driving and stopping mechanism of the illustrated machine is the same as disclosed in the Ashworth and Whitaker patent, above mentioned, and comprises a high-speed clutch 96 and a low-speed clutch 98 mounted on the sewing shaft 22. To engage the high-speed clutch 96 to drive the machine at high speed, a lever 100 acts on the clutch and is fulcrumed in the machine frame at 102. A downwardly extending treadle-

controlled rod 104 is arranged when depressed to shift the lever 100 toward clutch engaging position. When the treadle-controlled rod 104 is released, the high-speed clutch 96 is disengaged and the low-speed clutch 98 is automatically engaged for a part of a sewing cycle to reduce the speed of the sewing shaft and to bring the machine to rest with the stitch-forming devices in predetermined stopping positions.

Referring to Figs. 1 and 3, the mechanism for engaging and disengaging the low-speed clutch 98 includes a vibrating lever 106 having a follower engaging a cam on the sewing shaft 22, a spring-pressed lock bolt 108 mounted to slide vertically in a horizontally movable carrier 110 toward and from the vibrating lever, a link 112 connecting the lock bolt with one arm of a lever 114, and a cam arm 116 engaging a roll on the lever 114 and having pivotally connected to it the upper end of the treadle rod 104. When the treadle rod 104 is depressed, the lock bolt 108 is withdrawn from the vibrating member 106 to free the low-speed clutch 98 before the high-speed clutch 96 is engaged. At the end of a seam, when the treadle-controlled rod 104 is released and raised, the spring-pressed lock bolt 108 engages the vibrating lever 106 and enters a recess in the lever at a predetermined point in the sewing cycle to throw the low-speed clutch into operation and bring the machine to rest at a predetermined stopping position with the stitch forming devices and presser foot free of the work. When the lock bolt enters the recess in the lever 106, the connections, including the cable 76, also are shifted to throw the welt cutting knife mechanism into operation. The recess in the vibrating lever 106 comes into alignment with the lock bolt 108 over so large a part of each sewing cycle that there is a possibility that the welt knife may be actuated to cut the welt before the next to the last stitch of the seam is completed. Accordingly more than a single stitch may be formed in the welt beyond the cut or the operating parts may become damaged unless special provision is made to avoid such operation.

In order to insure actuation of the welt knife just before the final sewing cycle of the machine occurs, the lower end of the lock bolt has a rearward projection on which is pivoted a yieldingly actuated finger 118 disposed with its upper end in the path of movement of the vibrating lever 106. During sewing, when the lock bolt 108 is withdrawn from the recess in the vibrating lever, the finger 118 is held positively beneath the path of the vibrating lever and yieldingly against a rear surface of the lock bolt carrier 110. When the treadle-controlled rod 104 is released, the upper end of the finger 118 will engage the under side of the vibrating member and hold the lock bolt away from the recess in the vibrating member until the next to last sewing cycle is completed. Thereafter, the vibrating lever 106 will move clear of the finger 118, enabling the lock bolt to rise. Upon the return movement of the vibrating lever 106 the finger will be pressed out of the path of the vibrating member and the lock bolt will enter the recess in the lever 106 to set the welt cutting knife in readiness for operation before the final sewing cycle is completed.

As has been stated, a yieldable welt clamp is provided to cause the end of the welt at the cut formed by the knife to be severed when the completely sewed shoe is withdrawn from the machine. If the knife is actuated at the proper time, the final stitch inserted in the shoe passes

through both bevel surfaces of the cut formed by the knife as well as that portion of the welt on the shoe between the cut and the welt guide (see Fig. 25). When the shoe is withdrawn from the machine, the bevel cut end of welt remaining in the welt guide is torn loose from the final stitch, leaving a notch 119, illustrated in Figs. 26 and 29, at the end.

The welt clamp consists of a slotted plate 120 having at its upper end an offset flanged and recessed jaw portion formed to fit between flanges of a guide roll 122 for the welt as it passes from the supply to the welt guide (see Figs. 6 to 14 inclusive). From the guide roll, the welt passes first to a stationary guide tube 124 the upper end of which projects to a position in close proximity to the welt guide 25 in the work support 23. The welt clamp plate 120 is mounted upon a rotatable U-shaped carrier 126 having a flat sided hub which enters the slot in the clamp plate to guide the clamp plate for sliding movement diametrically of the carrier. The welt guide roll 122 is rotatably supported on a sleeve projecting from the hub of the carrier 126 through the central opening of which passes a shaft 127 rotatably supported in a mounting plate 128 and secured in the carrier 126 which surrounds the mounting plate. The mounting plate 128 is clamped to a support bracket 130 bolted on the frame of the machine. The plate 128 has an arcuate groove 132 cut in its under side within which fits an arcuate projection of the bracket 130. The center of the arcuate groove and projection coincides with the center of the shaft on the plate 128, the plate being adjustably clamped to the bracket 130 by a bolt 134 passing through an arcuate slot in a flange of the bracket and into threaded engagement with the plate. When the welt clamp plate 120 is moved downwardly on the carrier 126 toward the center of the guide roll 122, its jaw portion compresses the welt against the guide roll, there being a pair of pointed screws 136 in the jaw portion of the plate 120 to bite into the flesh surface of the welt and grip it securely against slippage. When raised to move its jaw portion away from the roll 122, the plate 120 releases the welt so that it is free to pass over the roll.

With the parts in the position of Fig. 8, the welt is free for movement toward the welt guide and the shoe during normal sewing operations. As soon as the driving and stopping mechanism is thrown into operation, the welt clamp plate 120 is actuated into the position of Fig. 9 to grip the welt on the roll 122. When the shoe is freed from the machine at the end of a seam and is being withdrawn by the operator, the welt clamp plate, together with the roll and the carrier 126, is rotated by the movement of the welt to the position of Fig. 10, thus enabling the cut in the welt to be drawn past the sewing point ready for a new operation on the shoe, as illustrated in Fig. 26. At the same time the welt is severed at the cut, the ends of sewing thread attached to the shoe are trimmed by a suitable hand knife, indicated at 138 in Fig. 26.

To return the welt clamp plate 120 with the carrier 126 from the position of Fig. 10 to its starting position after severing the welt, the flanged portion of the plate has a pin 140 to which is connected a spring 142 stretched between the pin and the machine frame. To prevent the bevel cut end of the welt remaining in the machine from being retracted from the welt guide when the clamp plate is returned to its

starting position after the welt end is completely severed from the shoe, the flanged portion of the clamp plate is formed with a slot 144 into which enters the upper end of a plunger 146, the lower end of which is pressed by a spring 148. The plunger 146 is slidably mounted in a slot of the plate 128, and the spring 148 is seated against the lower end of the slot where it is compressed by the plunger. To hold the spring 148 under compression, the upper end of the plunger bears against an abutment pin 150 in the plate 128 while the clamp plate is in welt releasing position. When the clamp plate 120 is moved to grip the welt, the flange on the plate engages the upper end of the plunger 146 and depresses it. Thereafter, upon rotation of the clamp by the welt, the slot 144 moves into alignment with the plunger 146 to latch the clamp plate and restrain it in rotated position, thus preventing further rotation of the clamp plate with the welt and further retraction of the severed end of the welt from the work support. As soon as the clamp plate is moved to release the welt, the plunger 146, which remains stationary against the abutment pin, is withdrawn from the slot 144, thus enabling the clamp plate and carrier to be returned to their starting positions without retracting the welt.

To actuate the welt clamp into gripping relation with the welt, the lower end of the clamp is perforated to receive the reduced end of one arm on a lever 152 fulcrumed on a pivot 154 secured by lugs projecting downwardly from the carrier 126. Another arm of the lever 152 projects upwardly toward the axis of the shaft 127 and is engaged by a compression spring 156 carried within a perforation at the rearward headed end of the shaft 127. Also engaging the upwardly extending arm of lever 152 is a ball-shaped portion on an arm 158 fulcrumed on a stud screw 160 threaded in the bracket 130. The points of engagement between the ball portion of the arm 158 and the arm on the lever 152 are substantially concentric with the center of shaft 127 about which the carrier 126 rotates so that the position of the clamp on the welt is not changed during rotation of the carrier. The arm 158 is engaged by the forward end of a rod 162 the rearward end of which is pivotally connected to an arm 164 (see Fig. 3) of the driving and stopping mechanism. When the driving and stopping mechanism is actuated at the end of a seam, the arm 164 is given a forward movement and is latched in its forward position in a manner explained more fully in the patent to Ashworth and Whitaker above identified. During this forward movement, the rod 162 presses the arm 158 which, in turn, rocks the lever 152 and slides the welt clamp plate 120 downwardly against the welt. This operation occurs in the final sewing cycle of the machine at the same time that the presser foot is unlocked and raised from engagement with the shoe to release the shoe. The clamp plate thus prevents the welt from being withdrawn from the machine except to the extent required in carrying the cut in the welt past the sewing point. After being severed, the cut end of the welt is held by the clamp plate in the position of Figs. 26 and 27 to be engaged by the stitch forming devices in starting a new seam.

The nature and scope of the invention having been indicated and a particular embodiment having been described, what is claimed is:

1. In a sewing machine for use in the manufacture of shoes, the combination with stitch

forming devices acting to secure a welt progressively to a shoe, and a welt guide for directing the welt into a position on the outturned shoe upper in advance of the sewing point, of a knife constructed and mounted for operation between the welt guide and the point of operation of the stitch forming devices on that portion of the welt in actual contact with the shoe.

2. In a sewing machine for use in the manufacture of shoes, the combination with stitch forming devices acting to secure a welt progressively to a shoe, and a welt guide for directing the welt into a position on the outturned shoe upper in advance of the sewing point, of a knife constructed and mounted for operation on that portion of the welt in actual contact with the shoe at a location a fraction of a stitch length ahead of the sewing point.

3. In a sewing machine for use in the manufacture of shoes of the stitchdown type, the combination with stitch forming devices acting to secure a welt progressively to the outturned upper and projecting sole margin of a shoe, and a welt guide for directing the welt into a position on the outturned shoe upper in advance of the sewing point, of a knife constructed and mounted for operation on that portion of the welt in sewing position contacting with the shoe to cut the welt against the substance of the shoe upper as a cutting block.

4. In a sewing machine for use in the manufacture of shoes of the stitchdown type, the combination with stitch forming devices acting to secure a welt progressively to the outturned upper and projecting sole margin of a shoe, and a welt guide for directing the welt to a position on the outturned shoe upper through a bend at the point of contact with the upper, of an elongated knife constructed with a sharpened edge at the end nearest the shoe and slidably mounted in the welt guide for operation against the welt along the bend at the point of contact of the welt with the upper.

5. In a sewing machine for use in the manufacture of shoes of the stitchdown type, the combination with stitch forming devices acting to secure a welt progressively to the outturned upper and projecting sole margin of a shoe, and a welt guide disposed at an angle to the outturned surface of the shoe upper operated upon to form a bend in the welt as it comes into contact with the upper, of an elongated knife constructed with a sharpened edge at the end nearest the shoe and mounted to cut the welt along the bend against the substance of the upper as a cutting block.

6. In a sewing machine for use in the manufacture of shoes of the stitchdown type, the combination with stitch forming devices acting to secure a welt progressively to the outturned upper and projecting sole margin of a shoe, a welt guide disposed at an angle to the outturned surface of the shoe upper operated upon to form a bend in the welt at the point of contact with the upper, of a knife mounted to cut the welt along the bend, and driving and stopping mechanism acting, when thrown into operation during sewing, to cause the knife to cut the welt less than a stitch length from the sewing point and then to bring the machine to rest after the succeeding stitch has been inserted.

7. In a sewing machine for use in the manufacture of shoes of the stitchdown type, the combination with stitch forming devices acting to secure a welt progressively to the outturned upper

and projecting sole margin of a shoe, a welt guide disposed at an angle to the outturned surface of the shoe upper operated upon to form a bend in the welt at the point of contact with the upper, of a knife mounted to cut the welt along the bend without separating the ends completely, welt clamping means for gripping the welt to prevent its withdrawal with the shoe from the machine when the machine is brought to rest, and a driving and stopping mechanism acting, when thrown into operation during sewing, to cause the knife to cut the welt and the welt clamping means to grip the welt.

8. In a machine for use in attaching welt to a work piece, the combination with devices acting to secure the welt progressively to the work piece, and a welt guide for directing the welt into position on the work piece in advance of the attaching point, of a knife constructed and mounted to cut the welt at the end of the securing operation without separating the ends completely, and yieldable welt clamping means for gripping the welt to limit the amount of welt withdrawn from the machine when brought to rest to a length required in carrying the cut section of the welt past the point of operation of the securing devices.

9. In a machine for use in attaching welt to a work piece, the combination with devices acting to secure the welt progressively to the work piece, and a welt guide for directing the welt into position on the work piece in advance of the attaching point, of a knife mounted to cut the welt without separating the ends completely, welt clamping means, and a driving and stopping mechanism for the machine acting, when thrown into operation, to cause the knife to cut the welt and the welt clamping means to limit the amount of welt withdrawn from the machine to the length required in carrying the cut section of welt past the point of operation of the securing devices.

10. In a sewing machine for use in the manufacture of shoes, the combination with stitch forming devices acting to secure a welt progressively to a shoe, a welt guide, of a knife mounted to form a bevel cut in the welt extending from the guide, and driving and stopping mechanism acting when thrown into operation during sewing to cause the knife to cut the welt and then cause the stitch forming devices to insert a stitch intersecting the bevel cut in the welt.

11. In a sewing machine for use in the manufacture of shoes, the combination with stitch forming devices acting to secure a welt progressively to a shoe, a welt guide, of means severing the welt at the end of a seam and for locating the end of the welt remaining in the guide at a position where it will be engaged by the stitch forming devices at the start of a new seam, comprising a knife mounted to form a cut in the welt extending from the guide without severing the welt completely, driving and stopping mechanism acting when thrown into operation during sewing to cause the knife to cut the welt and then cause the stitch forming devices to insert a stitch connecting the final end of the welt on the shoe with the first end, and a welt clamp acting to limit the length of welt withdrawn while removing the shoe from the machine at the end of a seam to that required in carrying the end of welt remaining in the machine past the point of operation of the stitch forming devices and to cause the welt to be severed by the pull exerted during continued removal of the shoe.

12. In a sewing machine for use in the manu-

facture of shoes, the combination with stitch forming devices acting to secure a welt progressively to a shoe, a welt guide, and welt clamping means, of a knife mounted to cut the welt extending from the welt guide, and driving and stopping mechanism acting when thrown into operation during sewing to cause the knife to cut the welt, to continue the operation of the stitch forming devices thereafter until a stitch connecting the ends of the welt on the shoe has been inserted, to actuate the welt clamping means into gripping relation with the welt after the stitch forming devices have inserted the final stitch, and then to bring the machine to rest with the stitch forming devices in stopping positions.

13. In a sewing machine, the combination with stitch forming devices, of a guide for directing a welt into position on the work in advance of the sewing point, a guide roll from which the welt passes to the welt guide, a carrier rotatable about the center of the guide roll, a clamp on the carrier for gripping the welt on the guide roll to cause the carrier and clamp to be rotated when welt is withdrawn with the work from the machine at the end of a seam, a stop for limiting rotation of the carrier while the clamp grips the welt, yielding means for returning the carrier to its starting position, and a latch for preventing return of the carrier to its starting position except after the clamp releases the welt.

14. In a sewing machine, the combination with stitch forming devices, of a guide for directing a welt into position on the work in advance of the sewing point, a guide roll from which the welt passes to the welt guide, a carrier rotatable about the center of the guide roll, a clamp on the carrier movable diametrically of the guide roll for gripping the welt on the guide roll to cause the carrier and clamp to be rotated when welt is withdrawn from the machine, a stop for limiting rotation of the carrier when the clamp grips the welt, yielding means for returning the carrier to its starting position, and a latch actuated yielding away from the center of the roll and arranged for engagement with the clamp while gripping the welt to prevent return of the carrier to its starting position and to be disengaged from the clamp while the clamp is releasing the welt.

15. In a sewing machine, the combination with stitch forming devices, of a guide for directing a welt into position on the work in advance of the sewing point, a guide roll from which the welt passes to the welt guide, a carrier rotatable about the center of the guide roll, a clamp on the carrier movable diametrically of the guide roll for gripping the welt on the guide roll to cause the carrier and clamp to be rotated when welt is withdrawn from the machine, a stop for limiting rotation of the carrier when the clamp grips the welt, yielding means for returning the carrier to its starting position, a latch actuated yielding away from the center of the roll and arranged for engagement with the clamp while gripping the welt to prevent return movement of the carrier to starting position, and an abutment for the latch to hold the latch out of engagement with the clamp when the clamp is moved to release the welt.

16. In a sewing machine for use in the manufacture of shoes, the combination with stitch forming devices acting to secure a welt progressively to a shoe, a welt guide for directing the welt towards the point of operation of the stitch forming devices, of a knife constructed and

mounted to cut the welt without severing the ends completely, and yieldable welt clamping means for gripping the welt to limit the amount of welt withdrawn from the machine when brought to rest, to a length required for carrying the cut section of the welt past the point of operation of the stitch forming devices.

17. In a sewing machine, the combination with stitch forming devices of a guide for directing a welt to a position on the work in advance of the sewing point, a guide roll from which the welt passes to the welt guide, a bracket on which the guide roll is rotatable, a carrier rotatable on the bracket concentrically with the guide roll, a welt clamp slidable on the carrier diametrically of the guide roll and provided with a flanged portion extending over the periphery of the guide roll, a stop on the bracket for limiting rotation of the carrier and clamp with the welt while being gripped by the clamp, a spring for returning the carrier to starting position after the clamp is rotated with the welt, a sliding plunger on the bracket, a spring for actuating the plunger yielding against the flanged portion of the clamp while gripping the welt to latch the clamp in the position to which it is rotated by the welt, and an abutment on the bracket for the latch to restrain the latch when the clamp is moved to release the welt.

18. In a machine for use in attaching welt to a work piece, the combination with devices acting to secure the welt progressively to the work piece, and a welt guide for directing the welt into position on the work piece in advance of the attaching point, of a knife mounted to cut the welt in advance of the sewing point, driving and stopping mechanism acting when thrown into operation during sewing to cause the knife to cut the welt and then to bring the machine to rest, and means arranged to hold the knife inoperative to cut the welt when the driving and stopping mechanism is actuated between the ends of a seam, including a member arranged for manual actuation during sewing to render the knife operative to cut the welt when the driving and stopping mechanism is actuated.

19. In a machine for use in attaching welt to a work piece, the combination with devices acting to secure the welt progressively to the work piece, a welt guide for directing the welt into position on the work piece in advance of the attaching point, and driving and stopping mechanism for bringing the machine to rest at the end of a seam, of a knife mounted to cut the welt in advance of the sewing point, normally inoperative mechanism for actuating the knife including connections between the driving and stopping mechanism and the knife mechanism for setting the knife actuating mechanism in operation, and means controlled manually during sewing for rendering the knife mechanism setting connections effective or for holding them ineffective when the driving and stopping mechanism is actuated.

20. In a machine for use in attaching welt to a work piece, the combination with devices acting to secure the welt progressively to the work piece, a welt guide for directing the welt into position on the work piece in advance of the attaching point, and driving and stopping mechanism for bringing the machine to rest at the end of a seam, of a knife mounted to cut the welt in advance of the sewing point, mechanism for actuating the knife, a latch for holding the knife mechanism inoperative, and connections between the driving

and stopping mechanism and the latch of the knife mechanism for releasing the knife mechanism from the latch when the driving and stopping mechanism is actuated to stop the machine.

21. In a machine for use in attaching welt to a work piece, the combination with devices acting to secure the welt progressively to the work piece, a welt guide for directing the welt into position on the work piece in advance of the attaching point, and driving and stopping mechanism for bringing the machine to rest at the end of a seam, of a knife mounted to cut the welt in advance of the sewing point, mechanism for actuating the knife, a latch for holding the knife mechanism inoperative, connections between the driving and stopping mechanism and the latch of the knife mechanism for releasing the knife mechanism from the latch when the driving and stopping mechanism is actuated to stop the machine, and means rendered inoperative manually during sewing for disconnecting the latch from said connections.

22. In a sewing machine for use in attaching welt to a work piece, the combination with stitch forming devices, a sewing shaft for actuating the stitch forming devices and a welt guide for directing the welt into position on the work piece in advance of the sewing point, of a knife mounted to cut the welt in advance of the sewing point, and mechanism for actuating the knife, including a cam on the sewing shaft, a follower cooperating with the cam, a pivoted support on which the follower is movable, a latch on the support for holding the follower out of engagement with the cam, and means for disengaging the latch from the follower, including a manually operable member arranged to be actuated during sewing operations.

23. In a sewing machine for use in attaching welt to a work piece, the combination with stitch forming devices, a sewing shaft for actuating the stitch forming devices and a welt guide for directing the welt into position on the work piece in advance of the sewing point, of a knife mounted to cut the welt in advance of the sewing point, mechanism for actuating the knife, including a cam on the sewing shaft, and a follower cooperating with the cam, a latch for holding the follower away from the cam, connections between the driving and stopping mechanism and the latch, comprising a hook member for actuating the latch away from the follower, and a manually actuated latch for holding the hook member away from the follower holding latch arranged when actuated to cause the hook member to engage the follower holding latch.

24. In a sewing machine for use in attaching welt to a work piece, the combination with stitch forming devices, a sewing shaft for actuating the stitch forming devices and a welt guide for directing the welt into position on the work piece in advance of the sewing point, of a knife mounted to cut the welt in advance of the sewing point, mechanism for actuating the knife, including a cam on the sewing shaft, and a follower cooperating with the cam, a latch for preventing more than one operation of the follower and for holding the follower away from the cam, connections between the driving and stopping mechanism and the latch, including a hook member arranged when actuated first to release the follower from the latch and thereafter to become disconnected from the latch, and a manually operable latch for releasably holding the hook member in disconnected position.

25. In a sewing machine, the combination with stitch forming devices and a guide for directing a welt to the work operated upon in advance of the sewing point, of a knife mounted for operation on a portion of the welt while in sewing position on the work, driving and stopping mechanism acting when thrown into operation during sewing to cause the knife to cut the welt and then to bring the machine to rest after a stitch has been inserted passing through the welt at the side of the cut nearest the welt guide, and welt clamping means acting when the work is withdrawn from the machine to cause the end of welt extending from the welt guide to be separated from the work.

26. In a sewing machine for use in the manufacture of shoes of the stitchdown type, the combination with stitch forming devices and a guide for directing a welt into a position on the out-turned upper of a shoe in advance of the sewing point, of a knife mounted for operation upon a portion of the welt while in sewing position on the shoe upper, driving and stopping mechanism acting when thrown into operation during sewing to cause the knife to cut the welt and then to bring the machine to rest after a final stitch in the seam has been inserted passing through the welt at the side of the cut nearest the welt guide, and welt clamping means acting when the shoe is withdrawn from the machine to cause the welt extending from the welt guide to be torn loose from the final stitch.

27. In a sewing machine, the combination with stitch forming devices and a guide for directing a welt to the work operated upon in advance of the sewing point, of a knife mounted for operation upon a portion of the welt while in sewing position on the work to form a bevel cut in the welt, driving and stopping mechanism acting when thrown into operation during sewing to cause the knife to cut the welt and then to bring the machine to rest after a final stitch in the seam has been inserted passing through the bevel surfaces of the welt at either side of the cut, and welt clamping means acting when the work is withdrawn from the machine to cause the bevel cut in the end of the welt extending from the welt guide to be torn loose from the final stitch.

28. In a sewing machine, the combination with stitch forming devices acting to secure a welt progressively to a work piece, a welt guide, of a knife mounted to cut the welt, driving and stopping mechanism acting when thrown into operation during sewing to cause the knife to cut the welt and then to cause the stitch forming devices to insert a stitch, and means for preventing the knife from being actuated before the next to last stitch is completed.

29. In a sewing machine, the combination with stitch forming devices acting to secure a welt progressively to a work piece, a welt guide, a knife mounted to cut the welt, mechanism for actuating the knife, driving and stopping mechanism for bringing the stitch forming devices to rest at the end of a seam, comprising a vibrating lever, a spring-pressed lock bolt movable toward and from the vibrating lever to throw the driving and stopping mechanism into operation, and a control rod

for withdrawing the lock bolt from the vibrating lever, of connections between the knife actuating mechanism and the lock bolt for causing the knife to be actuated when the lock bolt engages the vibrating lever.

30. In a sewing machine, the combination with stitch forming devices acting to secure a welt progressively to a work piece, a welt guide, a knife mounted to cut the welt, mechanism for actuating the knife, driving and stopping mechanism for bringing the stitch forming devices to rest at the end of a seam, comprising a vibrating lever, a spring-pressed lock bolt movable toward and from the vibrating lever to throw the driving and stopping mechanism into operation, and a control rod for withdrawing the lock bolt from the vibrating lever, of connections between the knife actuating mechanism and the lock bolt for causing the knife to be actuated when the lock bolt engages the vibrating lever, and a finger for preventing the lock bolt from engaging the vibrating lever before the next to last stitch in a seam is inserted.

31. In a sewing machine for use in attaching a welt to a work piece, the combination with stitch forming devices, a sewing shaft for actuating the stitch forming devices, a welt guide for directing the welt into position on the work piece in advance of the sewing point, and driving and stopping mechanism including a lock bolt and treadle controlled lock bolt actuating connections for bringing the machine to rest at the end of a seam, of a knife mounted to cut the welt in advance of the sewing point, normally inoperative mechanism driven from the sewing shaft for actuating the knife, and connections between the treadle controlled connections and the knife actuating mechanism, for setting the knife mechanism in readiness for operation by the sewing shaft before the machine is brought to rest.

32. In a sewing machine for use in attaching a welt to a work piece, the combination with stitch forming devices, a sewing shaft for actuating the stitch forming devices, a welt guide for directing the welt into position on the work piece in advance of the sewing point, and driving and stopping mechanism for bringing the machine to rest at the end of a seam, including a vibrating lever, a bolt acting when released to lock the vibrating lever, and treadle controlled lock bolt actuating connections, of a knife mounted to cut the welt in advance of the sewing point, normally inoperative mechanism driven from the sewing shaft for actuating the knife, and connections between the lock bolt connections and the knife actuating mechanism, for setting the knife mechanism in readiness for operation when the lock bolt engages the vibrating lever.

33. In a sewing machine for use in the manufacture of shoes, the combination with stitch forming devices acting to secure a welt progressively to a shoe, a welt guide, of a knife mounted to cut across the welt, and driving and stopping mechanism acting when thrown into operation during sewing to cause the knife to cut the welt and then cause the stitch forming devices to insert a stitch intersecting the cut in the welt.

FRED ASHWORTH.
